(57) **CLAIM**

The ornamental design for an octagonal pole with reinforcing members, as shown and described.

DESCRIPTION

FIG. 1 is a top plan view of an octagonal pole with reinforcing members, the bottom plan view being a mirror image; FIG. 2 is a side elevational view thereof; FIG. 3 is a perspective view thereof; and, FIG. 4 is a second perspective view thereof, shown in environmental use.

The broken lines shown represent unclaimed subject matter and form no part of the claimed design.

The octagonal pole with reinforcing members is shown broken to represent indeterminate length. The indeterminate portion of the article forms no part of the claim design. Patentability is based only on those portions of the octagonal pole with reinforcing members that are shown in solid lines.
